UNITED STATES PATENT OFFICE.

FREDERICK SAMUELSON, OF RUGBY, ENGLAND, ASSIGNOR TO GENERAL ELECTRIC COMPANY, A CORPORATION OF NEW YORK.

GOVERNING MECHANISM FOR ELASTIC-FLUID TURBINES.

No. 811,249.

Specification of Letters Patent.

Patented Jan. 30, 1906.

Application filed March 23, 1905. Serial No. 251,550.

To all whom it may concern:

Be it known that I, FREDERICK SAMUELSON, a subject of the King of Sweden and Norway, residing at Rugby, England, have invented certain new and useful Improvements in Governing Mechanism for Elastic-Fluid Turbines, of which the following is a specification.

My invention relates to the governing of steam or other elastic-fluid turbines of the type in which the steam is admitted to the turbine through a number of nozzles. In machines of this character the regulation of the power developed is effected by controlling the number of nozzles in operation so as to vary the volume of steam admitted in accordance with the load, and in order that this regulation may be accomplished with economy—that is, with the minimum of throttling at the main throttle-valve—it has been customary to provide a valve for each of the nozzles. This arrangement, however, especially in large machines, involves the use of a large number of valves, which take up a large amount of valuable space and add considerably to the cost of construction of the machine.

The object of my invention is to simplify the controlling mechanism by reducing the number of valves which it is necessary to employ without impairing the efficiency of regulation.

My invention consists in dividing up the admission-space into sections of different volume or groups of nozzles containing different numbers of nozzles or nozzle-sections and in controlling each section or group of nozzles by a separate valve.

In carrying my invention into effect according to one modification as applied to a steam-turbine having, for example, ten inlet-nozzles I divide these inlet-nozzles into four groups, the first group containing one nozzle, the second two, the third three, and the fourth four nozzles, and I fit the inlet to each of these groups of nozzles with a valve, thereby employing only four valves in all. As the total number of inlet-nozzles is ten, if it be assumed that all the valves are open at full load then each nozzle will admit one-tenth of the steam required, and by arranging the valve-operating gear to close certain of the valves, leaving the others open, the amount of steam admitted may be regulated to with-

in ten per cent. of the total from full load down to one-tenth load. Thus, for example, if the first valve be closed ninety per cent. of the total steam would be admitted, and if the first and fourth valves be closed only fifty per cent. of the steam will be admitted, the first valve shutting off one inlet-nozzle and the fourth shutting off four. Fifty per cent. of the steam might also be admitted by closing the second and third valves and opening the first and fourth. By this method of grouping ten nozzles under the control of four valves the same regulation may be obtained as formerly would have required ten separate valves. It will be obvious that by the addition of a fifth valve controlling a group of five nozzles regulation could be obtained to within one-fifteenth of the total steam admission.

It will be understood that in addition to the above I may control the steam-supply by means of a throttle-valve in the usual manner.

Instead of the above-described method of grouping the inlet-nozzles I may employ various other arrangements. For example, if I employ four valves; as before, I may provide four sections containing, respectively, one, two, four, and eight nozzles, each controlled by one of the valves, and with this arrangement regulation to within a fifteenth of the total steam capacity of the nozzles may be obtained. By adding more valves, each valve controlling a group of twice the number of inlet-nozzles contained in the last preceding group, finer regulation may be obtained with a comparatively small number of valves. Thus with six valves controlling groups containing one, two, four, eight, and sixteen inlet-nozzles, respectively, I can obtain regulation to within one thirty-first of the total power supplied.

Instead of arranging the valves to control each a different number of inlet-nozzles the same result will be obtained if the valves control single nozzles of different capacity.

It will be obvious that although I have described above specific examples of grouping the nozzles under the valves my invention is not limited to these, as numerous other arrangements might be adopted without departing from the spirit of the invention. For example, a number of groups of nozzles each having the same capacity in combination

with one or two groups having smaller capacities upon which the finer control and throttling is effected may be employed.

The operation of the valves may be effected 5 either mechanically or electrically, and the groups should be arranged so that as far as possible the steam delivered to the turbine at each change of load enters through adjacent nozzles, so that the fluid stream is kept practically continuous, thereby diminishing the 10 loss due to spilling at the nozzle ends.

In the accompanying drawings, Figure 1 is 15 a diagrammatic view of one embodiment of my invention. Fig. 2 is a chart showing the order of opening the valves, and Fig. 3 is a development of a controller for operating the valves electrically, and Fig. 4 is a diagrammatic view of another embodiment of my invention.

According to the modification of the invention illustrated in Figs. 1 to 3 I employ a set 20 of ten nozzles of equal size arranged in four groups of one, two, three, and four nozzles, respectively. In order to maintain the continuity of the stream of elastic fluid passing 25 through said nozzles, the groups are arranged in the order two, four, one, three. Each group is supplied with steam from an individual chamber 2, to which it is admitted 30 from a common steam-chest 3 by a single valve. This makes only four valves for the ten nozzles. They are designated as A B C D. Each valve can be separately operated by suitable devices. I have illustrated 35 an electropneumatic system of control in which the valves are actuated by steam-pressure, which is in each case controlled by a small auxiliary valve operated by an electromagnet 4. The several magnet-coils are 40 connected by wires 5 with fingers 6, adjacent to a controller-drum 7, on which are groups of contact-segments 8. One terminal of a generator 9 is connected with said segments, said magnet-coils being connected in multi- 45 ple with the other terminals thereof. The drum is operatively connected with the governor 10 of the turbine, as by means of the levers 11, rods 12, rack 13, and pinion 14. The governor oscillates the drum to and fro, 50 which brings different rows of segments in contact with the fingers and energizes different magnet-coils to cause the valves to open and shut. The drawings show that when valve C is open one nozzle is in use, giving ten 55 per cent. of the total power. When valve A is open and C is shut, two nozzles are used, giving twenty-per-cent. power. The valves D and B, respectively, open three and four nozzles, increasing the power to thirty and 60 forty per cent., the other three valves being shut in each case. To obtain fifty-per-cent. power, five nozzles must be opened, so that the controller-drum is arranged to open valves B and C simultaneously. For sixty- 65 per cent. power, A and B are opened; for sev-

enty per cent., A, B, and C; for eighty per cent., B C D; for ninety per cent., A B D, and for the maximum power all the valves are opened. In every combination but one (that of A B D) the nozzles in use are adjacent, so 70 that there is no division of the stream of elastic fluid.

If there are fifteen nozzles arranged in four groups of one, two, four, and eight, respectively, the increase of power can be by one- 75 fifteenth at a time, the order in which the four valves are opened and closed being considerably more complicated, but easily effected by a proper controller-drum.

In the embodiment of my invention illustrated in Fig. 4 I have shown a nozzle-section containing twelve nozzles divided up into four groups of nozzles, two of which contain two nozzles each and the remainder four nozzles. The groups are controlled by separate 80 valves A' B' C' D', and a throttle-valve E is arranged to control the fluid supplied through one of the smaller groups. The nozzle-valves are operated under the control of the governor-operated controller 7' in a similar manner to the arrangement shown in Fig. 1. The actuating member 13 in this case, however, instead of being directly connected to the valve-operated rod 12 is connected to a rod 15, pivotally attached to one end of a lever 90 16, which at its opposite extremity is connected to the stem of the throttle-valve E. This lever is attached at an intermediate point to the governor-operated rod 12, which acts on the lever against the force of an adjustable controlling-spring 17, by means of which the mechanism may be adjusted for operation at different speeds. If we assume that the nozzle-section illustrated passes the total amount of fluid supplied to the turbine 105 and that the machine is working under a light load corresponding to, say, one-sixth full load, then the valve B' will be open. The controller-contacts may be arranged so that for half-load the valves B' and C' will be 110 open and for two-thirds load the valves A' B' C' will be open, the whole of the valves being open for full load. With the controlling mechanism arranged as illustrated and the controller-drum requiring greater power to 115 operate than does the throttle-valve it will be seen that as the governor operates under a change in load conditions the throttle-valve E will first be moved and then the drum of the controller 7' by the action of the governor mechanism on the lever 16. For example, if we assume that the machine is working under light load the throttle-valve E and the valve B' will be open, and if the load varies slightly the change in load will be 120 taken care of by the throttle-valve. If now the load is increased to, say, half-load, the throttle-valve will open to its full extent and then the controller will be moved so as to cause the valve C' to open, any variation in 125 130

load being taken care of by the throttle-valve. Similarly, if the load diminishes the throttle-valve will first be operated to completely cut off the supply of fluid through the 5 nozzles controlled by the valve B', and then the controller will be operated so as to cause closure of a valve or valves, so as to meet the altered load condition.

The operation of the throttle-valve always 10 precedes that of the controller, and when a given load condition is established corresponding to certain grouping of the nozzle-valves slight variations in load are met by movement of the throttle-valve. As this 15 valve acts on the fluid supplied through the nozzle-passage of smallest capacity, the regulation is accomplished with the minimum loss due to throttling.

The arrangement of governing mechanism 20 for operating the controller and throttle-valve forms no part of the present invention. It is similar in construction and operation to that described in Emmet and Junngrens application, Serial No. 156,142, filed May 8, 1903. 25 It will be understood that in the embodiment of my invention just described the load-steps mentioned are only illustrative of one method of operation. In practice instead of the total supply of fluid being passed through 30 a single nozzle-section it would probably be divided between at least two sections. The nozzles of one of these sections might be divided into groups of equal capacity, each group being controlled by a valve, the other section being similar to that illustrated in 35 that it has two or more groups of nozzles of unequal capacity with the throttling-valve operating on one of the groups of smaller capacity. With this change it will be obvious 40 that a large number of load-steps might be obtained. In general the number required is determined by the size of the machine and the special conditions under which it is required to operate.

45 It will therefore be seen that my invention provides a simple and effective means for increasing and diminishing the speed of an elastic-fluid turbine by comparatively small increments. I thus reduce first cost and main- 50 tenance, expense, lessen the liability of breakdowns, and render the engine easier to understand and handle.

In accordance with the provisions of the 55 patent statutes I have described the principle of operation of my invention, together with the apparatus which I now consider to represent the best embodiment thereof; but I desire to have it understood that the apparatus shown is only illustrative and that the 60 invention can be carried out by other means.

What I claim as new, and desire to secure by Letters Patent of the United States, is—

1. In a governing mechanism for an elastic-fluid turbine, the combination of a number 65 of discharge-passages having different ca-

pacities, individual valves for controlling the passage of fluid therethrough and a means for effecting different combinations of the valves to compensate for different loads on the turbines.

2. In a governing mechanism for elastic-fluid turbines, the combination of an admission-passage which is divided into sections having dissimilar capacities, individual and similarly-weighted valves for controlling the 75 passage of fluid through said sections, and a means responsive to speed variations for effecting different combinations of the valves to compensate for different loads on the turbines.

3. In a governing mechanism for elastic-fluid turbines, the combination of an admission-passage which is divided into sections having dissimilar carrying capacities, individual valves for controlling the passage of 85 fluid therethrough, a regulator which opens and closes the valves in a predetermined order as it moves from the initial to the final position to gradually increase the supply of motive fluid delivered to the wheel, and a device responsive to load changes for moving the regulator.

4. In a governing mechanism for an elastic-fluid turbine, the combination of a number of discharge-passages having different 95 capacities, individual valves for controlling the passage of fluid therethrough a means for effecting different combinations of the valves and means for regulating the supply of fluid through a passage having the smallest capacity.

5. In a governing mechanism for an elastic-fluid turbine, the combination of a number of discharge-passages having different 105 capacities individual valves for controlling the passage of fluid therethrough a means for effecting different combinations of the valves and a throttle-valve acting on the fluid supplied to a passage having the smallest capacity.

6. In a governing mechanism for an elastic-fluid turbine the combination of a number of discharge-passages having different capacities, individual valves for controlling the passage of fluid therethrough a regulator constructed and arranged so as to cause the opening and closing of the valves in predetermined groups, each group including a valve controlling a passage of the minimum capacity and a throttle for regulating the discharge of fluid through said passage.

7. In a governing mechanism for an elastic-fluid turbine, the combination of a number of discharge-passages having different 125 capacities, separate valves controlling said passages, a regulator constructed and arranged to cause the opening and closing of said valves in predetermined groups, a throttle-valve acting upon the fluid supplied to a passage of minimum capacity and speed-re- 130

sponsive mechanism acting upon said regulator and throttle-valve.

8. In a governing mechanism for elastic-fluid turbines, the combination of an admission-passage which is divided into sections having dissimilar carrying capacities, individual valves for controlling the passage of fluid therethrough, a regulator constructed and arranged to first open the valve of the passage having the least capacity, then open the valve of the passage having the next greater capacity and close the first, and so on until each valve has been in service, and finally to group valves in a manner to further increase the supply of fluid to the turbine to the maximum, and a speed-regulating device for moving the regulator.

9. In a governing mechanism for an elastic-fluid turbine, the combination with groups of nozzles of different carrying capacities, of a separate valve for each group, and means for opening and closing said valves in such order that the successive quantities of elastic fluid delivered shall increase by regular increments measured by the capacity of the smallest nozzle.

10. In a governing mechanism for an elastic-fluid turbine, the combination with groups of nozzles of different carrying capacities, of a separate valve for each group, and means for opening and closing said valves in such order that the successive quantities of elastic fluid delivered shall increase by regular increments, measured by the reciprocal of the total number of nozzles, from zero up to the total nozzle capacity.

11. In a governing mechanism for an elastic-fluid turbine, the combination with groups of nozzles whose cross-sectional areas vary by multiples of a given constant, of a separate valve for each group, and means for opening and closing said valves singly and in

combination in order to utilize one or more groups of nozzles to deliver quantities of elastic fluid successively increasing by multiples of the reciprocal of the total number of nozzles.

12. In a governing mechanism for an elastic-fluid turbine, the combination with groups of nozzles of different carrying capacities arranged side by side, of a separate valve for each group, and means for opening and closing said valves in such a predetermined order that the varying quantity of elastic fluid thereby delivered shall flow from nozzles that are adjacent.

13. In a governing mechanism for an elastic-fluid turbine, the combination with groups of nozzles of different carrying capacities, of a separate valve for each group, and means for opening said valves both singly and in combinations of two or more, whereby the quantities of elastic fluid delivered will increase in the arithmetical progression of a unit equal to the capacity of the smallest group.

14. In a governing mechanism for an elastic-fluid turbine, the combination with groups of nozzles of different carrying capacities of a separate valve for each group, means responsive to changes in the load on the turbine, and operative connections whereby said means causes the opening and closing of said valves in order that said nozzles shall deliver quantities of elastic fluid successively increasing or decreasing by multiples of the reciprocal of the total number of nozzles.

In witness whereof I have hereunto set my hand this 11th day of March, 1905.

FREDERICK SAMUELSON.
